DISK GRINDING MACHINE

Fred M. Hargrave, Cedar Rapids, Iowa

Application July 2, 1934, Serial No. 733,486

2 Claims. (Cl. 51—106)

My present invention relates generally to grinding machines, and more particularly to machines for grinding and sharpening the concavo-convex disks such as are used in connection with harrows in heavy duty farm work as well as the scarifying, reworking and planing of oiled bituminous and sheet asphalt roads and pavements.

It is the primary object of my invention to provide, in a manner as hereinafter set forth, a simple, effective rapid grinding and sharpening machine which may be operated continuously over considerable periods without the necessity of replacement or truing of the grinding wheel.

The means by which I accomplish the desired results, as well as the further and more specific objects of my invention and the resulting advantages thereof, will be better understood and more thoroughly appreciated from the following detailed description of my invention and its various structural parts and operations, having reference to the accompanying drawings, which form a part of this specification, and in which,

Figure 1 is a top plan view of my improved disk grinding machine.

Figure 2 is a side elevation thereof, certain parts being broken away and in section.

Figure 3 is an enlarged vertical longitudinal section through the work holding and rotating parts.

Figure 4 is a similar view through the grinding wheel and its arbor holding arm.

Figure 5 is an enlarged end view of the arbor holding arm, and

Figure 6 is a diagram showing the manner in which the grinding wheel is applied to the disk.

Referring now to these figures, my invention is shown as mounted upon a stand or supporting frame 10, the only feature of importance of which as regards my invention being that it affords an upper horizontal top piece 11. Thus the supporting legs 12 inclined from this top piece may be varied as convenience suggests, so long as the stand as a whole is efficiently anchored.

Across the top piece 11, adjacent to one side thereof, is a work shaft support consisting of an elongated casing 13 provided with outstanding feet 14 near its ends connected by bolts or suitable anchoring members 15 to the stand. This casing 13 is hollow throughout, with open ends into which are fitted roller bearings 16 for the spaced bearing portions 17 of the work shaft 18 thus mounted to freely rotate axially of the casing.

The roller bearings 16 abut shoulders annularly of the shaft 18 between its bearing portions 17

and its central enlarged portion 19 within the casing 13, and are held against such abutments by end plates 20 and 21 which are secured to the forward and rear ends of the casing, as by means of bolts, to close said ends whereby the interior of the casing may form an oil reservoir, oil being provided thereto through a side oil inlet fitting 22.

Outwardly beyond the end plates 20 and 21, the work shaft 18 has reduced forward and rear extensions 23 and 24, upon the latter of which is secured a pulley 25 which may be belt connected to any suitable source of power for rotating the work shaft at high speed.

On the forward extension 23 of the shaft, the work, a disk 26, may be clamped between inner and outer circular axially apertured clamping members 27 and 28, the disk being placed on the shaft extension 23 with a bushing 29 around the latter to interfit the axial opening of the disk and insure its concentric disposition with respect to the shaft 18. Obviously it will be necessary to provide bushings of various diameters for this purpose, and it is equally plain the clamping members 27 and 28 will be formed on one face 25 with offset beveled marginal binding surfaces. The said surfaces extend in opposite directions with respect to each other and are indicated at 27', 28' to engage the concave and convex faces of the disk 26, since it is desired to mount the latter with its convex face presented forwardly.

To secure the work in place as above, the shaft extension 23 is threaded at its forward free end for the reception of a clamping nut 30 which abuts the outer or forward clamping member 28, and the inner or rear member 27 preferably has an annular rearwardly projecting rib 31 which extends into an annular groove 32 in the front face of the end plate 20 so as to prevent entrance of the ground material into the shaft bearings.

Positioned upon the front end and transversely of the top piece 11 of the stand 10 is an adjustable supporting bracket 33 formed with an elongated slot 34 lengthwise thereof. The bracket 33 is adjustably connected to top piece 11 by a detachably clamping element 35. The bracket 33 includes a fixed vertically disposed forwardly opening yoke-shaped arm 36 at one end thereof. A vertical pivot 37 is secured to arm 36 for the purpose of pivotally connecting the inner end of a horizontally disposed grinding wheel carrying and positioning frame 38 with the bracket 33. The frame 38 is formed of an outer and an inner yoke-shaped part 38', 38'' respectively which open in an outwardly lateral direction with respect to

the length of said frame. The part 38' is of materially less width and depth than that of the part 38''. The parts 38', 38'' are flush at their open ends. The closed end of part 38'' extends 5 inwardly beyond the closed end of the part 38'. The rear side of part 38'' is formed by the arm 38''' arranged within arm 36 and supported upon the bottom of the latter. The bolt 37 extends through a vertical opening in the arm 38'''. The 10 forward side of part 38' is formed by an arm 39. The rear side of part 38' and the forward side of part 38'' is formed by an arm 40. The arms 39 and 40 having aligning openings 39', 40' respectively. The opening 40' is of greater diameter 15 than opening 39. The arrangement of the frame 38 in the manner as shown permits it to swing outwardly with its free end forwardly of the edge of the disk and with the pivot for its inner end positioned inwardly adjacent the disk.

20 The grinding wheel 41, is held between clamping collars 42 and 43 on the forward reduced extension 44 of the grinding shaft 45, by means of a clamping nut 46. This shaft 45 is journaled axially of the tubular housing 47 at one end of the grinding wheel supporting arm 48, through 25 roller bearings 49 within opposite ends of said housing. One end of the housing is closed by an end plate 50 bolted thereto and provided with an external annular groove 51 receiving a similar or 30 companion rib 52 of the adjacent wheel clamping collar 42. The other end of the housing 47 is closed by the end cap 53 and thus the hollow interior thereof forms an oil reservoir to which oil may be supplied through an oiling plug 54.

35 The arm 48 has at its other end an axially bored cylindrical extension 55 in approximately the body plane of the grinding wheel 41 and projecting away therefrom at right angles to the housing 47 and the grinding wheel axis. This 40 extension 55 is slidably disposed through the inner bearing extension 40 of the frame 38 previously mentioned and is keyed against rotation therein by a key 56 to lock the supporting arm at a rearward and downward angle as plainly 45 seen in Figures 1 and 2.

45 Passing through the opening 39', in arm 39 and the bore 57 of extension 55 to the rear end of said bore 57 is a slide rod 58 having its forward portion peripherally threaded, as at 58'. The rear end of extension 55 is formed diametrically thereof with spaced apertures 59 which open into the bore 57. Extending through the apertures 59 and the rear end of rod 58 is a pin 60 for coupling the extension 55 with the rod 58 to 50 provide for them to bodily shift in unison relative to arms 39 and 40. Encompassing the rod 58, forwardly of and abutting arm 39 is a revoluble handle member 61. The latter is internally threaded for engagement with the threads 58' of rod 58. The member 61 functions to shift the rod 58 forwardly and rearwardly with respect to the arms 39, 40. Surrounding the rod 58 and interposed between arm 39 and extension 55 is a coiled cushioning spring 62 for the grinding wheel 55 structure. The tension of spring 62 is increased or diminished on the adjusting of rod 58 by handle member 61. The opening 39' of arm 39 is of greater diameter than and has its wall spaced from rod 58. The latter is held at all times 60 concentrically with respect to the wall of opening 39' by the extension 55. The latter has a sliding fit with the wall of opening 40' of arm 40. The spring 62 and a portion of the extension 55 is arranged within the yoke-shaped part 38' of the 65 grinding wheel structure carrying and position-

ing frame 38. The major portion of the grinding wheel structure is arranged within the yoke-shaped part 38'' of the frame 38. The arms 39, 40 and 38''' are termed respectively outer, intermediate and inner arms of frame 38.

5 It becomes apparent from the foregoing that after clamping the disk to be sharpened, as for instance disk 26, upon the work holding shaft in the manner previously described, so that it is truly concentric with the shaft, the disk is rotated at 10 high speed, whereupon the operator grasps handle 61, having previously rotated this handle to place spring 62 under the desired tension, and swings the grinding wheel holding frame 38 horizontally and forwardly on its pivot 37 until the peripheral 15 face of the grinding wheel 41 comes into engagement with the disk at the convex side of its edge. When thus engaged with the work, it will be noted from the dotted line position of the parts in Figure 1, the axis of the grinding wheel 41 is at an 20 angle to the axis of the work holding shaft, and consequently the disk 26, of approximately 45 degrees, and its body plane will also approximate that degree of angularity with respect to the engaged portion of the work edge, as seen by reference to Figure 6, and by reason of the previously described inclination of the supporting arm 48 and the wheel shaft 45. It is obvious then that in the rotation of the disk, its material on the convex side of its edge will sweep angularly across 25 the peripheral face of the grinding wheel from one side to the other and the wheel will be gradually and uniformly rotated on its own axis so that in the grinding operation it will be worn down evenly and without the necessity of more or less 30 frequent refacing operations.

The operator controls to a considerable extent the pressure of the grinding wheel against the work, but this pressure is relieved in some measure by the spring 62 which permits the grinding 40 wheel to yield wherever inequalities of either the wheel or the work are present and wherever, for any other reason, binding is threatened.

45 My improved grinding and sharpening mechanism solves the problem of properly sharpening the modern alloy steel disks used in heavy duty, as far as general or casual use is concerned, and results in the removal of the material back of the cutting edge of the disk in such manner as to bring about a sharp cutting edge with maximum 50 material reenforcement of said cutting edge in much the same degree as the disk comes from the factory in the first instance.

No grinding is done on the concave side of the cutting edge, though in some instances it is necessary to remove the burr, if such develops, from the grinding of the convex side. For this purpose I may utilize a burr removing grinding wheel 63 shown only in Figure 2, mounted to rotate in connection with a lever 64 having a handle 65 on one 60 end, and having a pivot opening at its other end by which it may be applied, when used, upon the upper end portion of the pivot bolt 37. Thus the wheel 63 may be shifted against the concave side of the cutting edge of the disc without difficulty, 65 and may, like the grinding wheel 41, be set with its body at such angle between the plane of the disk and the plane of the axis of the disk, so as to bring about a cutting action across the entire peripheral face of the wheel and a uniform rotation thereof, minimizing and equalizing wear of the wheel with a constant truing of its grinding surface.

70 Furthermore, while not in any manner essential to my invention, the safety of the operator 75

may be preserved during use of the grinding mechanism by any suitable guards, both for the rotating disk 26 and the grinding wheel 41, as I have indicated in a general way at 66 in Figure 2 and 67 in Figure 4.

What I claim is:—

1. In a disk grinding machine, a vertical support, a driven element carried by and extended at one end from said support, means for clamping the disk to be ground to the extended end of said element, a manually bodily shiftable swingingly mounted elongated horizontally disposed grinding wheel structure carrying and positioning frame, means for pivotally connecting the inner end of said frame to said support inwardly adjacent to the extended end of said element, a grinding wheel structure arranged within and depending from the frame and formed with a laterally extended part having the outer portion thereof slidably mounted in the body of said frame intermediate the ends of the latter for disposing said structure in depending relation and at an outward inclination, from its bottom to its top with respect to the frame, a cushioning means for said structure positioned within the frame forwardly of said portion, and an adjustable means carried by and lengthwise of the frame, permanently extending beyond the outer end of the frame, sup-
- porting said cushioning means and connected to said portion for selectively shifting said structure bodily in opposite directions with respect to the frame for varying the tension of said cushioning means.
2. In a disk grinding machine, a work holder, a bodily shiftable support pivoted at its inner end with and shiftable towards and from said work holder, a tubular housing open at each end, an imperforate closure for one end of the housing, an axially apertured closure for the other end of the housing, bearing means within the housing at each end thereof and spaced from said closures, a shaft extending through said bearings and apertured closure and projecting outwardly from the latter, a grinding wheel mounted on the projecting end of said shaft, means for clamping the wheel to the projecting end of said shaft, said means revolving in said apertured closure, and a supporting arm for, integral with and disposed at an angle to the housing and being formed at its outer end with a tubular extension disposed at right angles thereto, said extension being mounted in said support outwardly adjacent the pivoted end of the latter to provide for the housing being bodily carried by and suspended from the support.

FRED M. HARGRAVE.
